IGNITING PLUG FOR HAND GRENADES

Fernand Laguesse, Herstal, near Liege, Belgium

Application April 15, 1935, Serial No. 16,505
In Belgium April 18, 1934

4 Claims. (Cl. 102—29)

In the known hand grenades the control of the percussion is generally obtained by means of a catch lever or rod which tends to move away from the body of the grenade under the action of the percussion spring, and is held in the safety position by a pin or other equivalent member. Consequently in such grenades, the percussion takes place, after the safety device has been removed the catch lever is released whether the grenade is thrown or not.

It is, therefore, necessary to throw the grenade as soon as the pin holding the catch lever has been removed, but although the time to burn is about five seconds for the wick, ignited by the striker premature explosions have often occurred which have given rise to very serious accidents.

The object of the present invention is to increase the safety with which hand grenades can be manipulated by providing them with an igniting plug, the striker of which is liberated by a catch lever or an equivalent member only after the latter has effected a movement of fairly large amplitude, say for example a quarter of a turn, without this displacement influencing in any way the degree of tension of the striker spring.

Consequently as the catch lever is in no way urged by the striker spring to make this displacement, it remains in stable equilibrium in all the positions of large amplitude prior to the percussion proper.

This displacement will be produced either under the effect of a removal or by a ballistic action, for example, under the action of inertia, centrifugal force, etc.

If, in the usual manner, use is made of a pivoting catch lever, the displacement which is intended to retard the percussion when the grenade is thrown, is obtained by combining circular co-operating surfaces, one of which forms a track for the other, these surfaces being carried respectively by a catch lever and by an igniting plug or a member rigid therewith, so that the axis joining the centres of these surfaces passes through the centre of rotation of the catch lever.

Further, in order to seal the internal part of the grenade in a perfectly fluid tight manner, the tail of the striker is gripped in a sliding cover or cap engaged by the catch lever and applied hermetically upon the upper face of the igniting plug by the striker spring.

One embodiment of an igniting plug according to the invention is illustrated by way of non-limiting example in the accompanying drawing, in which:—

Figure 1 is a partial longitudinal section of the plug.

Figure 2 is a partial front view thereof.

Figure 3 is a plan view with an oblique section through the catch lever.

As in the known hand grenades, the body 1 of the plug is screwed upon the body of the hand grenade and comprises the exploder holder 2, carrying the priming cap 3, the relay 4 and the detonator 5.

In the body 1 is suspended the striker 6 having a spherical head and a conical shaped part 7 which bears upon a correspondingly shaped wall of a chamber 11' formed in a cover or cap 11 mounted upon the body with the interposition of a joint 12.

The conical tail 7 is gripped between the edge 9 of the body 1 and the edge 10 of the chamber 11' of the cover or cap 11.

The spring 8 seated on an annular shoulder in the hollow of the body 1 exerts a pressure upon the striker 6 which also has the effect of pressing the cover or cap 11 tightly against the upper face of the body 1 and of urging it at the same time to slide towards the left. But the cover 11 is locked in the cocked position by a catch lever 17 which encloses the cover, and has upon each of its lateral faces a beak or hook 18 adapted to engage a lug 19 rigid with the cover or cap 11 (Figure 3).

The line *aa* joining the points of contact *a* of the hook 18 with the lugs 19 constitutes the pivoting axis of the lever 17.

Furthermore, the body 1 is provided externally with a circular surface 20 having its centre on the line *aa* (Figure 3) and forming a track for a roller 21 pivoted at *b* upon the lever 17. As the straight line *a'b* connecting the centres of the arcuate surface 20 and of the roller 21 together cuts the axis of rotation of the lever 17 centrally, the latter is constantly in stable equilibrium as long as the roller 21 is in contact with the surface 20. A pin 16 locks the lever 17 in known manner in order to permit the grenade to be handled with safety.

Under these conditions, when the grenade is thrown after withdrawing the pin 16, the lever 17, under the action of centrifugal force pivots about the axis *aa* and moves further and further from the body of the grenade, its roller 21 running on the track 20 for a quarter of a turn, for example, until it finally leaves the curve 20. At this moment the lever 17 is thrown out of balance and is pulled off the grenade so that it liberates the cover which then moves to the left under the action of

the spring 8, and permits the striker 6 also to respond to the pressure of the spring 8 and fire the primer 3.

The centrifugal displacement of the lever 17 is 5 facilitated by the presence of a mass 22 fixed at its end.

As stated above numerous constructional modifications of the igniting plug according to the invention may be imagined; for example, the 10 roller 21 may be mounted on the body 1 of the plug, while the circular surface 20 will be provided upon or in the catch lever 17.

What I claim is:

1. In an igniting plug for hand grenades, a 15 sliding cover adapted to obturate the body of the plug, said cover having a chamber formed therein, a spring pressed striker mounted in said plug body and having a conical upper part gripped, in 20 its cocked position in the said chamber, between an edge of said cover within said chamber and an edge of the plug body, the spring pressing on the striker to cause the firing of the primer acting also to apply hermetically the sliding cover 25 against the plug body in the cocked position of the striker.

2. In an igniting plug for hand grenades, a 30 sliding cover adapted to obturate the body of the plug, a chamber internally formed in said cover, a spring pressed striker mounted in said plug body and having a conical upper part gripped in its 35 cocked position in the said chamber between an edge of said cover within said chamber and an

edge of the plug body, a catch member locked on the plug body by a safety pin, and adapted to enclose with its upper part the sliding cover, said catch member having notches cooperating with lugs provided on said sliding cover to hold the catch member in the cocked position, a circular surface formed externally on the plug body and constituting a track, and a revoluble member carried by the catch member engaged by said track. 5

3. An ignition plug for hand grenades comprising 10 a body member having an ignition chamber open at one end and containing a priming cap, an annular ledge adjacent said opening, a hollow cap covering said opening and provided with a bevelled edge near its center, a striker having an 15 enlarged head and a cone-shaped tail adapted to engage between said bevelled edge of the cap and said ledge in assembled position, a double acting spring inserted between said ledge and said striker head, whereby said striker is held in cocked position and said cap in assembled position closing 20 said opening; and detachable means adapted to lock said cap in such assembled position.

4. An ignition plug according to claim 3 in which said locking means consists of a lever the 25 fulcrum of which is situated in the longitudinal axis of said body member adjacent said opening, an arcuate cam on said body member coaxial with said fulcrum, a rolling surface on the lever contacting with said cam, and interengaging lugs 30 on the lever and the cap.

FERNAND LAGUESSE.
